[57] CLAIM

The ornamental design for a ten sided die, substantially as shown and described.

DESCRIPTION

FIG. 1 is a perspective view of the ten sided die showing my new design;

FIG. 2 is a top view thereof;

FIG. 3 is a left side view thereof;

FIG. 4 is a front view thereof;

FIG. 5 is a right side view thereof; and

FIG. 6 is a bottom view thereof.

The numerals shown in broken line in FIG. 1 are for explanatory purposes and do not form part of my ornamental design.
